UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

MOUNTING FOR HAMMER-DRILLS.

1,321,565.

Specification of Letters Patent.

Patented Nov. 11, 1919.

Application filed April 12, 1919. Serial No. 289,536.

To all whom it may concern:

Be it known that I, WILLIAM A. SMITH, a citizen of the United States residing at Easton, in the county of Northampton and 5 State of Pennsylvania, have invented a certain new and useful Improvement in Mountings for Hammer-Drills, of which the following is a specification.

This invention relates to rock-drills and 10 especially to a rock-drill of the hammer type in which the drill is mounted to slide forwardly and rearwardly in a shell. The invention in particular relates to the means employed by means of which a guide is 15 fastened to the drill having flanges adapted to enter the usual grooves provided in the sides of the shell.

The objects of the present invention are 20 to provide a means for mounting or fastening a guide upon the drill, the guide having means for slidably engaging a shell in which the drill and guide may be mounted. A further object is to mount the guide upon the drill by means of the same bolts used in 25 securing the several parts of the drill together. Another object is to provide a mounting which may be readily and conveniently connected and disconnected from the drill by simply removing and replacing 30 nuts on a pair of bolts mounted on the drill.

With the above and other objects in view, this invention consists in the features of construction and operation set forth in the following specification and claims and illustrated in the accompanying drawings, forming 35 a part hereof, in which

Figure 1 shows a longitudinal view of the drill and guide with the guide in operative position.

Fig. 2, a similar view of the guide removed.

Fig. 3, a perspective view of the guide.

Referring more particularly to the figures of the drawing, 1 refers generally to a drill 45 body or cylinder which may be of any desired type the one shown for purposes of illustration being of the hammer drill type for which the present invention is specially adapted. At 2 is shown the guide by means 50 of which the drill is held in slidable engagement with the usual shell, not shown. The guide 2 is provided with flanges 3 extending from either side of the guide throughout its entire length. The drill 1 is provided at its 55 forward end with a front head 4 provided

on either side with lugs 5 provided with suitable holes through which pass bolts 6 which also pass through holes provided in lugs 7 provided near the forward end of the drill cylinder or body portion. The bolts 6 60 are made sufficiently long to extend forwardly from the lugs 5 so that there is ample space on the bolts 6 to engage lugs 8 formed on the forward end of the guide 2. From the above description it will be seen that 65 nuts 9 located on the forward ends of bolts 6 will securely hold the forward end of guide 2 and the front head 4 to the drill body 1.

At the rear end of the drill body 1 is a 70 back head having lugs 11 extending from either side through which pass bolts 12 which are preferably in alinement with the bolts 6 at the forward end of the drill 1. Lugs 13 in alinement with lugs 11 are located near the rear end of drill body 1 so that bolts 12 may pass through suitably alined holes in both sets of lugs. Nuts 14 75 on bolts 12 allow the back head 10 to be securely held against the rear ends of the drill 80 body 1. On the heads 15 of the bolts 12 are provided integral extensions 16 which may be suitably tapered as clearly shown in Figs. 1 and 2.

Lugs 17 located near the rearward portions of the guide 2 are suitably bored as shown at 18 to provide depressions to correspond with the tapered extensions 16 on bolt heads 15 so that the lugs 17 will set over and engage the bolt head extensions 16 90 as shown in Fig. 1 by means of these depressions.

With the parts in the position shown in Fig. 1 the drill and guide are in operative position and ready for insertion in a drill 95 shell commonly used when the drill is used in a mounted position as in drifting. Should it be desired to replace the guide 2 with another, as, for instance, when the guide 2 becomes unduly worn, it is only necessary 100 to loosen nuts 9 and slip the lugs 8 from the bolts 6 and the guide 2 may be completely removed from the drill and another placed in its stead.

From the above it will be seen that means 105 have been provided which will securely hold the drill and guide in operative position relatively to each other and will also permit changing the guide readily and easily.

It is to be understood that the present 110

showing and description disclose only one specific embodiment of the present invention and that other forms and modifications are included within the spirit and scope of the 5 same as expressed in the appended claims.

What I claim is:

1. In combination, a drill, a guide for said drill and means to hold said drill and guide in operative position relatively to each other, comprising bolts engaging portions of said drill and guide near one end thereof and bolts engaging portions of the drill near the other end and having extensions engaging depressions provided in said guide.
- 10 2. In combination, a drill, a guide for said drill and means to hold said drill and guide in operative position relatively to each other, comprising bolts engaging portions of said drill and guide near one end thereof and bolts engaging portions of the drill near the other end and having extensions provided on the head ends of said bolts engaging depressions provided in said guide.
- 15 3. In combination, a drill, a guide for said drill, and means to hold said drill and guide in operative position relatively to each other, comprising bolts engaging portions of said drill and lugs on said guide near one end thereof and bolts engaging portions of the drill near the other end and having extensions engaging depressions provided in said guide.
- 20 4. In combination, a drill, a guide for said drill, and means to hold said drill and guide in operative position relatively to each other, comprising bolts engaging portions of said drill and lugs on said guide near one end thereof, and bolts engaging portions of the drill near the other end and having extensions provided on the head ends of said bolts engaging depressions provided in said guide.
- 25
- 30
- 35
- 40

5. In combination, a drill, a guide for said drill, and means to hold said drill and guide in operative position relatively to each other, comprising bolts engaging portions of said drill and guide near the forward end thereof, and bolts engaging portions of the drill near the rear end and having extensions engaging depressions provided in said guide.

6. In combination, a drill, a guide for said drill, and means to hold said drill and guide in operative position relatively to each other, comprising bolts engaging portions of said drill and lug on said guide near the forward end thereof, and bolts engaging portions of the drill near the rear end and having extensions engaging depressions provided in said guide.

7. In combination, a drill, a guide for said drill, and means to hold said drill and guide in operative position relatively to each other, comprising bolts engaging portions of said drill and guide near the forward end thereof, and bolts engaging portions of the drill near the rear end and having extensions provided on the head ends of said bolts engaging depressions provided in said guide.

8. In combination, a drill, a guide for said drill, and means to hold said drill and guide in operative position relatively to each other, comprising bolts engaging portions of said drill and lugs on said guide near the forward end thereof, and bolts engaging portions of the drill near the rear end and having extensions provided on the head ends of said bolts engaging depressions provided in said guide.

In testimony whereof, I have hereunto set my hand.

WILLIAM A. SMITH.

Witness:

FELIX AJALER.
